UNITED STATES PATENT OFFICE.

GEORGE L. BADGER, OF QUINCY, MASSACHUSETTS.

INTERNAL-COMBUSTION ENGINE.

1,260,297.

Specification of Letters Patent. Patented Mar. 26, 1918.

Application filed October 1, 1913. Serial No. 792,871.

To all whom it may concern:

Be it known I, GEORGE L. BADGER, a citizen of the United States, and a resident of Quincy, in the county of Norfolk and State of Massachusetts, have invented an Improvement in Internal-Combustion Engines, of which the following description, in connection with the accompanying drawings, is a specification, like characters on the drawings representing like parts.

This invention relates to internal combustion engines, and more especially, though not exclusively, to engines of the two cycle type, and will be best understood by reference to the following specification, when taken in connection with the accompanying drawings of two specific embodiments thereof, while its scope will be more particularly pointed out in the appended claims.

In the drawings:

Figure 1 is a vertical, cross-sectional view through one of the cylinders of the vertical, multi-cylinder, two-cycle, internal combustion engine embodying my invention;

Fig. 2 is a vertical, longitudinal section through one of the cylinders and a portion of another;

Fig. 3 is a vertical, cross-sectional view through one of the cylinders of another form or embodiment, showing a slight modification of the power cylinder in which the latter is extended to form also the circumferential wall of the compression cylinder;

Fig. 4 is a plan sectional view in a plane containing the exhaust ports and exhaust manifold;

Figs. 5, 6, 7 and 8, are vertical, cross-sectional views of the engine at a reduced scale, representing the parts of the engine in four different positions, and illustrating the action of the sliding valve with relation to the pistons;

Fig. 5 shows the engine in its initial position, or on dead-center,—that is to say, with the pistons at the top of their stroke, and the valve closed, ready for the spark;

Fig. 6 shows the pistons at mid-stroke descending;

Fig. 7 shows the pistons at the bottom of their stroke, the intake port being nearly closed and the exhaust port partially open;

Fig. 8 shows the pistons at mid-stroke ascending, the exhaust port being wide open, and the crank case port partly open; and

Fig. 9 is a perspective view at a reduced scale showing the crank-shaft in a conven-

tional way and illustrating the relation of the cranks.

Referring to the drawings, and to the embodiments of my invention which I have selected for illustration, and more particularly to Figs. 1, 2 and 4 to 8, inclusive, I have there shown an internal combustion engine having a crank shaft 10, which is preferably provided with a plurality of cranks, one of which is represented at 11.

When the engine is of the four-cylinder type, the cranks will be set so that the cylinders may be fired in 1—3—2—4 order, which will require the cranks to be arranged in pairs, and the cranks of each pair to be 180 degrees from each other, but in a plane at right angles to the plane of the other pair of cranks, as shown in Fig. 9.

The crank-shaft is mounted in appropriate bearings in a crank case 12, divided by walls 13 into a plurality of compartments 14, corresponding to the number of cylinders. The latter are substantially similar to each other in construction, though arranged in pairs. The engine herein comprises four cylinders, or cylinder units, which for convenience will be designated 15¹, 15², 15³, and 15⁴; but since, as already stated, these cylinders are substantially similar to each other, it will be necessary to describe only the cylinder 15¹, and a portion of the cylinder 15², in order that a clear understanding of the construction and operation of the engine may be had.

Each cylinder unit comprises an outer cylinder or casing 16, supported upon and secured to the crank case 12. This outer cylinder or casing is herein provided with an intake port 17, an exhaust port 18, a transfer passage 19, an air inlet port 20, a scavenging passage 21, and a starting air port 22, the location and purposes of which will be more particularly referred to hereinafter.

Located within and suspended from the upper end of the outer cylinder or casing 16 is a working cylinder 23, having a transfer port 24 for the release of the combustible mixture from the compression space to the transfer passage, an inlet port 25 for the admission of the explosive mixture from the transfer passage to the combustion chamber 26, an exhaust port 27 for the release of the burnt gases from the combustion chamber, a port 28 for the admission of scavenging air, and a port 29 for the admission of air to the combustion chamber for starting purposes.

The working cylinder may be, and preferably is, provided with a water jacket 30, enclosing a water space 31, intended to receive circulating water through an inlet pipe 32 and discharge the same through an outlet pipe 33.

Slidably mounted within the working cylinder 23 is a working piston 34, having appropriate piston rings 35. The working piston is herein provided with an annular groove 36, and one or more, preferably a plurality, of longitudinal passages 37, communicating with said groove. The purpose of this groove and these passages will be presently explained. The working piston is connected to its crank by a connecting rod 38, attached to a wrist-pin 39 passing through the piston and secured therein in a well known manner.

20 The working cylinder is separated from the outer cylinder or casing by an annular space 40, in which is disposed a sleeve 41, constituting a slide valve. This sleeve is herein provided with a port 42 for the admission of atmospheric air to the crank case through the port 20; a port 43 for the admission of the combustible mixture from the port 17 to the compression space herein-after described; a port 44 for the release 25 of the compressed combustible mixture from the port 24 to the exchange passage 19; a port 45 for the admission of the compressed combustible mixture from the transfer passage through the port 25 to the combustion 30 chamber 26; a port 46 for the release of the burnt gases from the combustion chamber through the port 27 to the port 18; a port 47 for the admission of scavenging air from the passage 21 through the port 28 into the 35 combustion space 26; and a port 48 for the admission of pressure fluid, such for example as compressed air, for starting purposes.

Within the sleeve 41 below the working cylinder 23, is a compressing piston 49, having one or more piston rings 50. In the form of my invention shown in Figs. 1, 2, and 4 to 8, inclusive, the circumferential wall of the compressing cylinder is formed 40 by the inner surface of the sleeve 41, while in the form shown in Fig. 3, the working cylinder is provided with a depending sleeve-like extension 51, which forms the circumferential wall of the compressing cylinder. In the latter case, the compressing piston is exactly similar to that shown in the first form, except that it is reduced in diameter by an amount equal to twice the thickness of the intervening depending 45 sleeve 51. In both cases, the compressing piston may be, and preferably is, formed on or secured to the working piston, and the annular space between the latter and the circumferential wall of the compressing cylinder constitutes what will be convenient to

term a compression space 52, the upper end of which is formed by the lower end of the working cylinder, and the lower end of which is formed by the upper end of the compressing piston.

Where it is desirable to obtain the highest practical thermal efficiency, and the size and weight of the engine are not of prime importance, the construction shown in Fig. 3 will preferably be employed. In this form, 75 the area of the annular surface of the compressing piston may be substantially one-half the area of the working piston, and the capacity of the combustion chamber or the clearance space of the power cylinder may 80 be reduced by one-half, so that the compression will remain substantially the same. With this form of construction, the gases will be expanded to nearly atmospheric pressure, before the exhaust port opens, and 85 there will be an increase of substantially 25 per cent, in thermal efficiency of the engine at full load, as compared with an engine that exhausts the gases at comparatively high pressure at full load. When it is desired to obtain a large power output from a given sized engine, the form shown in Figs. 1, 2 and 4 to 8 inclusive, which is the preferred form, will be employed. In this form, the area of the annular part of the 95 compressing piston is substantially the same as the area of the working piston.

The sliding sleeve may be operated by any other appropriate mechanism, but herein is connected by an eccentric rod 53, and an eccentric strap 54 to an eccentric 55, appropriately formed on or secured to the crank shaft 10. When the latter rotates, the sliding sleeve valve will be moved to cover and uncover the several ports which it controls 105 in their proper sequence in the operation of the engine, as will appear more fully herein-after.

The engine may be provided with any appropriate exhaust pipe or manifold, but in 110 order to increase the efficiency of the engine, and assist in thoroughly scavenging its cylinders, the engine is herein provided with an exhaust manifold designated generally by the numeral 56, provided with two chambers 57 and 58 formed by conduits 59 and 60, respectively, the inner chamber communicating with the exhaust ports of the cylinders 15' and 15². The conduit 59 is extended into the chamber 58 within the conduit 60, and has an outlet 61 within said chamber, said outlet being preferably beyond the exhaust port of the cylinder 15', and being preferably concentric with the outer conduit. Preferably also the inner 115 and outer conduits are tapered, or somewhat reduced in diameter, as shown in Fig. 4. It will thus be seen that when the piston of either pair reaches mid-stroke on its exhaust stroke, one of the pistons of the other 120 125 130

pair will have reached the end of its power stroke and the rush of the exhaust gases from the one cylinder through the pipe connected to its respective chamber will create 5 a strong suction in the pipe connected with the other chamber, thereby reducing the back pressure upon the first-mentioned piston, and assisting the scavenging air in clearing the combustion space of such cylinder of 10 spent gases before the combustible mixture is admitted to such cylinder.

The engine may be provided with any 15 usual or suitable ignition system, such for example as an electric jump-spark system similar to those in common use, and including a spark-plug 62 for each of the cylinders. As already stated, the firing of the engine will be in 1-3-2-4 order, that is to 20 say, the arrangement of the ignition system will be such as to cause a spark first in the cylinder 15', then in the cylinder 15³, then in the cylinder 15², and finally in the cylinder 15⁴.

The general operation of the engine herein- 25 before specifically described is as follows:—

Assuming that the parts are in the position shown in Fig. 5, and that a charge of compressed combustible gas is within the combustion space, and the crank is traveling 30 in the direction shown by the arrow in Fig. 5, the pistons descend from the position shown in Fig. 5 toward the position shown in Fig. 6. The sleeve valve also descends from the position shown in Fig. 5 toward 35 the position shown in Fig. 6, and during such time, the port 43 is in communication with the intake port 17, with the consequence that the descending compressing piston 49 draws in the charge of combustible mixture 40 from the intake port into the annular compression space 52. The piston continues to descend until it reaches the position shown in Fig. 7, the sleeve now ascending but the admission port being still partly open. 45 Thus it will be seen that the admission port is open during substantially the whole of the suction stroke. In the meantime, a charge of atmospheric air previously taken 50 into the crank case from the ports 20 and 42 is compressed by the descending pistons, and is forced through the scavenging passage in communication with the crank case compartment to the combustion chamber of the adjacent working cylinder, which at 55 that time is exhausting, since its piston is on the early part of its up-stroke. When the piston of the first-mentioned cylinder commences its upward stroke, the port 43 in the sleeve will pass upwardly into communication 60 with, and beyond, the intake port 17, as shown in Fig. 8, and the combustible mixture in the annular compression space will be partially compressed. Meantime, the 65 port 42 has risen into communication with the port 20, thus allowing the piston in its

up-stroke to suck atmospheric air into the crank case and the interior of the hollow pistons. When during the upward motion of the pistons the annular groove 36 commences to communicate with the port 24, the compressed combustible mixture will pass from the compression space 52 through the passage or passages 37 and annular groove 36 to the port 24.

At practically the beginning of the up- 70 stroke of the working piston, the port 46 in the sleeve establishes communication between the combustion space 26 and the atmosphere by way of the ports 27 and 18, thus releasing the burnt gases and allowing 75 them to be expelled. To assist in expelling the burnt gases, the air which is compressed in the crank case compartment 14 of the adjacent cylinder passes upwardly through the scavenging passage 21 through the port 47 in the sleeve, and through the port 28, into the working cylinder at a point practically opposite the exhaust port, the result 80 being that the scavenging air thus supplied to the cylinder cools the latter internally, 85 and assists in expelling the burnt gases. As already stated, owing to the use of the described type of exhaust manifold, the latter serves to assist in scavenging the cylinder, due to the suction which it creates in the 90 exhaust. In the meantime, when the working piston passes upwardly beyond the exhaust port 27, the ports 44 and 45 in the valve are still open to ports 24 and 25 respectively, and the partially compressed combustible mixture in the compression space 52 is forced from the port 24, by way of the transfer passage 19 and port 25, into the combustion chamber 26. The sleeve valve then descends until the port 45 is out of register with the port 25, at which time the working piston 34 is substantially at the end of its upward stroke. Either at, or 95 slightly before the dead-center, the charge is ignited and explodes, thus driving the working piston downward again. This completes 100 the cycle of operations. It will be observed that the several ports remain open substantially throughout the respective strokes of the piston, and are closed quickly at substantially the beginning and end of the 105 respective strokes of the piston, admitting comparatively large volumes of combustible mixture and air to the cylinder and crank-case, respectively, thus avoiding negative 110 work of the engine, and preventing in a large measure wire-drawing and heating of the gases passing through the ports. It will also be observed that a single positively operated slide valve controls the admission 115 and exhaust of gases to and from the combustion chamber, the admission and discharge of the combustible mixture to and from the compression chamber, the admission and discharge of scavenging air to and 120

125

130

from the crank-case, and the admission of compressed air to the power cylinder for starting the engine.

Moreover, owing to the construction of the engine and the arrangement of its ports, the disadvantages heretofore existing in the use of the crank-case for scavenging purposes are overcome, and the amount of power required for supplying the scavenging air to the power cylinder is very slight. There is, consequently, little liability of leakage of either air or oil from the crank-case, since the pressure in the crank-case is but slightly above atmospheric pressure. Since the ports can be made of large area and remain open during substantially the whole of the respective strokes of the piston, the pressure above or below atmospheric pressure in the crank-case will be only sufficient to cause the air to travel through the ports and passages at the required speed. The action of the scavenging air in clearing the cylinder of spent gases is greatly assisted, and the pressure required to force the air through the cylinder is much reduced by the novel manner in which the inertia of the exhaust gases in the manifold is utilized to supplement the action of the scavenging air.

While I have herein shown and described two specific embodiments of my invention for illustrative purposes, and have disclosed and discussed in detail the construction and arrangement incidental to two specific applications thereof, it is to be understood that the invention is limited neither to the mere details or relative arrangement of parts, nor to its specific embodiments herein shown, but that extensive deviation from the illustrated forms or embodiments of the invention may be made, without departing from the principles thereof.

Having thus described my invention, what I claim and desire by Letters Patent to procure is:—

45 1. In an internal combustion engine, the combination of an outer cylinder, an inner power cylinder separated from said outer cylinder by an annular space, a tubular valve encircling said power cylinder, and a piston having two diameters the smaller working in the bore of said power cylinder and the larger working within said valve.

2. In an internal combustion engine, the combination of an outer cylinder, an inner power cylinder located within and separated from said outer cylinder by a space, said cylinders being provided with inlet, transfer and exhaust ports, a tubular valve encircling said power cylinder and controlling said ports, a piston having two diameters the smaller working in said power cylinder and the larger working within said valve, there being an annular compression space encircling said smaller diameter, and means permitting the transfer of a compressed

charge of combustible mixture from said compression space to said working cylinder.

3. In an internal combustion engine, the combination of an outer cylinder, an inner power cylinder located within and separated from said outer cylinder by a space, said cylinders being provided with inlet, transfer and exhaust ports, a tubular valve encircling said power cylinder and controlling said ports, a piston having two diameters the smaller working in said power cylinder and the larger working within said valve, there being an annular compression space encircling said smaller diameter, said smaller diameter of said piston being provided with a recess registering with said transfer ports when the piston approaches the end of its exhaust stroke.

4. In an internal combustion engine, the combination of an inner power cylinder having an inlet and a transfer port, an outer cylinder having an inlet port and a transfer passage the latter adapted to communicate with said ports in the power cylinder, and a slide valve intermediate said cylinders for controlling said ports.

5. In an internal combustion engine, the combination of an outer cylinder, a power cylinder disposed within and spaced from said outer cylinder, a tubular valve encircling said power cylinder, and a piston having two diameters the smaller of which is disposed within said power cylinder and the larger of which is disposed within said tubular valve.

6. In a two cycle internal combustion engine, the combination of an outer cylinder provided with inlet, transfer and exhaust ports, a power cylinder provided with inlet, transfer and exhaust ports, pistons working in said cylinders, a slide valve intermediate said cylinders and provided with a plurality of ports, and means for operating said valve to cause its ports to register with the respective ports in said cylinders during substantially the whole of the respective strokes of the piston.

7. In a two cycle internal combustion engine, the combination of an outer cylinder provided with inlet, exhaust and transfer ports, an inner power cylinder provided with inlet, exhaust and transfer ports, a piston working in said power cylinder and provided with an enlarged portion at its lower or inner end forming a compression piston, and a slide valve intermediate said cylinders for controlling said ports, the smaller part of said piston being provided with a recess arranged to register with said transfer ports when the piston approaches the end of its exhaust stroke.

8. In a two cycle internal combustion engine, the combination of a closed crank-case, an outer cylinder secured thereto and provided with a transfer passage opening into

5 said crank-case, an inner power cylinder disposed within and supported by said outer cylinder and provided with a port arranged to register with the upper end of said transfer passage, a slide valve intermediate said cylinders, and means for operating said valve to cause the same to control said port.

9. In a multi-cylinder two cycle engine, the combination of a closed crank-case provided with a plurality of separate compartments corresponding to the cylinders, and a plurality of cylinder units each comprising an outer cylinder secured to said crank-case and provided with a scavenging passage 10 opening at one end into an adjacent compartment of the crank-case, an inner power cylinder supported by said outer cylinder and provided with a port adapted to communicate with the other end of said scavenging passage, and a slide valve intermediate said cylinders for controlling said port.

15 10. In a multi-cylinder internal combustion engine, the combination of a closed crank-case provided with a plurality of compartments corresponding to the cylinders, and a plurality of cylinder units each comprising an outer cylinder secured to said crank-case and provided with an inlet port leading into the corresponding compartment and a scavenging passage leading 20 from an adjacent compartment, an inner cylinder supported by said outer cylinder, and means for causing a charge of air to be taken into a crank-case compartment and transferred through said scavenging passage into said inner cylinder, the last-mentioned means including a slide valve intermediate said inner and outer cylinders.

25 11. In a multi-cylinder internal combustion engine, the combination of a closed crank-case provided with a plurality of compartments corresponding to the cylinders, and a plurality of cylinder units each comprising an outer cylinder provided with a transfer passage opening into one of said compartments, a power cylinder provided with a port arranged to register with said transfer passage, a piston working in said power cylinder, a slide valve intermediate 30 said outer and power cylinders provided with a port, and means for operating said valve to cause its port to register with said port in the power cylinder during substantially the whole of the exhaust stroke of the piston.

35 12. In a two cycle internal combustion engine, the combination of an outer cylinder provided with an inlet port and a transfer passage, an inner power cylinder provided 40 with a transfer port adapted to communicate with said transfer passage, a valve sleeve coöoperating with said ports, a piston in said power cylinder provided with an enlarged portion at its lower or inner end 45 forming a compression piston, the smaller

portion of said piston being provided with a recess adapted to register with said transfer port in the power cylinder when the piston approaches the end of its exhaust stroke, a crank-shaft, and a connecting rod 70 connecting said piston to said crank shaft, said transfer port in the power cylinder being located on the opposite side of the crank-shaft from the connecting rod when the piston is on its compression stroke. 75

13. In a two cycle engine, the combination of a power cylinder provided with an inlet port, an exhaust port and a transfer port, a piston in said cylinder provided with an enlarged portion at its lower end 80 forming a compression piston, the smaller portion of said piston being provided with a recess adapted to register with said transfer port when the piston approaches the end of its exhaust stroke, said exhaust port 85 being so placed as to be covered by the upper end of the piston just before the recess in the piston registers with said transfer port.

14. In an internal combustion engine, the combination of a plurality of cylinders provided with inlet and exhaust ports, pistons working in said cylinders in paired relation to each other, and an exhaust manifold connected to said cylinders, said manifold being divided into separate chambers, one pair of cylinders exhausting into one chamber and the other pair exhausting into the other chamber, the respective cylinders of one pair exhausting alternately with relation to 90 the respective cylinders of the other pair, said manifold having a conduit leading from one of said chambers through the other. 95

15. In a two cycle internal combustion 105 engine, the combination of a plurality of cylinders provided with inlet and exhaust ports, pistons working in said cylinders in paired relation to each other, the pistons of one pair being at opposite ends of their respective cylinders when the pistons of the other pair are at mid-stroke, and an exhaust manifold having two separate chambers, one pair of cylinders exhausting into one chamber and the other pair exhausting into the 110 other chamber, said manifold having a conduit leading from one chamber through the other. 115

16. In an internal combustion engine, the combination of a plurality of cylinders provided with inlet and exhaust ports, pistons working in said cylinders, a crank-shaft having cranks connected to said pistons to operate the same in paired relation to each other, the cranks connected with each pair of pistons being 180 degrees from each other and substantially 90 degrees from the cranks connected with the other pair of pistons, and an exhaust manifold having separate chambers, one pair of cylinders exhausting into 120 125 130

one chamber and the other pair exhausting into the other chamber, said manifold having a conduit leading from one chamber through and concentric with the outlet of the other chamber.

17. An explosion engine having, in combination, a casing provided with a chamber extending therethrough and having inlet and exhaust passages communicating with 10 said chamber, a cap adapted to close one end of said casing, a sleeve extending from said cap into said chamber and terminating substantially midway thereof and constituting an explosion cylinder, said sleeve having 15 inlet and exhaust passages, a sleeve valve interposed between said sleeve and said casing,

said valve having inlet and exhaust ports adapted to align with said passages, means to move said valve, and a piston arranged to reciprocate in said casing, said piston having two bearing members, one of said members adapted to fit said sleeve and the other of said members adapted to fit said valve in close proximity to the end of said sleeve.

20

25

In testimony whereof, I have signed my name to this specification, in the presence of two subscribing witnesses.
